UNITED STATES PATENT OFFICE.

LEONARD CHARLES BYGRAVE, OF LONDON, ENGLAND, ASSIGNOR TO THE RELAY AUTOMATIC TELEPHONE COMPANY, LIMITED, OF LONDON, ENGLAND.

TELEPHONE SYSTEM.

1,234,623.

Specification of Letters Patent.

Patented July 24, 1917.

Application filed January 19, 1916. Serial No. 72,967.

To all whom it may concern:

Be it known that I, LEONARD CHARLES BYGRAVE, a subject of the King of Great Britain, residing at Marconi House, Strand, 5 London, England, have invented new and useful Improvements in Telephone Systems, of which the following is a specification.

This invention relates to automatic and semi-automatic telephone systems which utilize relays instead of step by step electro-mechanical devices.

The principal object of the invention is to reduce the number of relays required on such systems already known, to simplify the 15 connections, to give greater flexibility and to simplify wiring and maintenance.

The invention refers to switching units made up of relays which may be associated one with each subscriber's line or junction to 20 give access to a plurality of other lines, or may be associated with a plurality of subscribers' lines, as for example, when used as a calling line finder.

The switching unit may be associated with 25 either an assignor which automatically and instantly causes the switch to connect a calling line to an idle junction line or with a responder which responding to impulses completes or assists to complete circuits to 30 a particular line or group of lines.

The invention is illustrated in the accompanying drawings in which Figure 1 shows switching units employed as calling line finders while Fig. 2 shows switching units 35 employed as connectors. Fig. 3 shows in single line diagram a two-digit switching unit. Fig. 4 shows the circuit of a calling line finder switching unit in which the next idle junction is pre-selected.

40 Fig. 5 shows the circuit of a direct calling two-digit switching unit combined with a responder.

In Fig. 1 the switching units S^a , S^b , S^c consisting of the two parts T and U give 45 any of the lines L, which may be calling, access to one of the associated junctions J^a , J^b , J^c . As a junction J^a , for instance, is taken into use it is of course made busy so that the switching unit S^b associated with 50 the next idle junction J^b is used. Such a switching unit is a calling line finder pre-selector.

In Fig. 2 the switching units S^a , S^b , S^c are 55 shown associated one with each subscriber's line L and act as direct calling pre-selectors

to find an idle junction J. They may also be employed to connect L to a particular junction J determined by an associated impulse responder.

In Fig. 3 a switch is shown arranged to 60 give a line J access to one of a plurality of lines L or to give one of a plurality of lines L access to a line J according to whether the switch is used as a pre-selector or as a calling line finder.

The switch is shown as consisting of four- 65 teen relays a to n , ten of which a to j respond and switch according to units im- pulses, while the remaining four relays k to n respond and switch according to the 70 tens impulses received; thus, if the relay a is operated, all those lines, the unit digit of which is 1, are connected to the ten wires p and if relay k is also operated the top wire p and therefore number 11 will be connected 75 to the junction J by circuit 11, all the other wires p being isolated at one or other of the contacts of the relays k to n . If relays a and l are operated, line 21 is connected. If b , m and n are operated, O^2 is connected 80 and so on, the connection of other numbers being easily traceable.

In Fig. 4 circuits are shown for two 2-digit switching units acting as calling line finders, 85 as in Fig. 1. Each unit is shown arranged to give forty lines access to one junction. Only four levels are shown corresponding to levels 71 to O^1 of Fig. 3. That figure shows the usual ten levels for a 100 line switch. Each level actually consists of three wires, 90 one from each of the groups A, B, C, making up a level. A and B are the talking circuits and C the test wires. Two subscribers are represented at X whose number let us assume is O^1 , and Y whose number let us 95 assume is 84, and two junctions at J^a , J^b . When a subscriber, X for instance, calls by taking his receiver off the switch hook (not shown) he completes circuit 2 through line relay X^2 and a common relay A. X^2 and A 100 operate, the former connecting negative potential to certain of the code wires C W, and the latter connecting the test wires T W of all the junctions to the assignor A^s. As- suming that all the junctions J^a , J^b are idle, 105 none of the assignor relays, except B which is a battery switching relay, will be ener- gized. B is operated in circuit 3 and com- pletes circuit 4 through relay C which oper- ates and switches all the coding wires C W 110

to switching unit S^a . In order to connect line X , O^1 , to a junction, it is necessary to operate relays a , m and n of the switching unit, therefore X^2 is arranged to connect the negative side of battery to the three coding wires associated with those three relays over circuits 5, 6 and 7. a , m and n on operating connect X to junction J^a over circuit 8 and through relay D , which may be directly or indirectly associated with the junction loop at the same or the next stage. D operates and completes circuit 9 through cut off relay E and through a , m and n in parallel. a , m and n are therefore maintained as long as the subscriber has his receiver off the switch hook. The operation of E cuts out relay X^2 and A , the former cutting circuits 5, 6 and 7, the latter releasing assignor A^s . If while the first junction is busy another subscriber, Y , No. 84, for instance, originates a call, circuit 10 will be completed through relays Y^2 and A , Y^2 connecting code 11, 12, 13 to code wires C W , and A connecting test wires T W to assignor A^s . Junction J^a being busy, circuit 14 is completed through assignor relay F which operating completes circuit 15 through relay G to connect the code wires to the relays of the second switching unit S^b . Code 11, 12, 13 will therefore cause relays y^d , y^k and y^n to operate connecting line Y over circuit 16 to junction J^b . Relay H will therefore operate to complete circuit 17 operating cut off relay Y^{10} and locking y^d , y^k and y^n .

The switch would then be associated with a junction as shown in Fig. 2. For the first series of impulses one or more of the relays k to n will be energized, and in answer to a second series one of the relays a to j will be energized. Thus line J , Fig. 3, would be connected to a particular one of the lines L . k to n may, for instance, control connection to the tens and a to j connection to the units.

In a further modification of the invention the unit may be arranged so that the responder itself forms part of the unit.

Fig. 5 shows circuits of a switching unit in which an impulse responder first initially energizes switching relays in response to one set of digit impulses and then, after completing preparatory circuits, in response to another set of digit impulses the resultant particular relays associated with the digit remain energized to switch a connection through and to maintain the circuit during connection.

The responder consists, as described for instance in British specification No. 1470 of 1915, of relays H , I , J , K , L , M , N , O . After responding to impulses of the first of two digits the responder momentarily completes a circuit to energize one of a group of relays associated with the "tens" digit which then locks itself in a local circuit. When the responder energizes by the second digit im-

pulses, certain relays of the responder, corresponding to the digit sent, energize and lock themselves in local circuits and remain so locked during the period of conversation, after having joined the calling line through 70 to one circuit of ten in the "tens" group previously called.

Circuit 1 corresponds to a circuit from a subscriber's instrument but may be completed by a repeater or other device, at a 75 previous stage. In this circuit 1^E is energized, when a call is made, to complete circuit 2 in which 2^E is energized. 2^E is slow to release so that when 1^E energizes and de-energizes according to the impulses received, 80 2^E will not have time to de-energize and certain circuits will therefore be kept energized during the impulses. 2^E completes circuit 3 in which 3^E is energized. It is to be noted that circuit 3 is completed over responder 85 relays H , I , J , K so that when one of these relays is energized for a period long enough 3^E will de-energize. 3^E completes circuit 4 to energize L . 2^E completes a holding circuit 5 over the previous switching stage. A circuit 90 6 is completed in which 6^E is energized but serves no useful purpose at the moment and has nothing to do with this invention. Digit switching relay 7^E is energized in circuit 7. It will be assumed that No. 11 is to be called. 95 When circuit 1 is opened on the break of the first impulse, 1^E is de-energized and circuit 8 is completed to energize H as is a retaining circuit 9 for L .

When 1^E is energized at the completion of 100 the first impulse a retaining circuit for H is completed over circuits 10 and 4. Circuit 11, completed at two points, namely, by 7^E and 2^E , energizes M . L de-energizes as circuit 8 is broken at 1^E . H and M only remain 105 energized at this stage. As, however, H has opened circuit 3 relay 3^E de-energizes, which cuts earth off circuit 4 so that H de-energizes. M is maintained energized by earth at 7^E . 3^E de-energizing completes circuit 12 to energize 110 No. 1 switching relay 12^E of the tens digit switch which is then retained in a local circuit 13 to earth at 2^E . This happens in the time interval between the opening of the circuit 7 at 3^E and the de-energization of 7^E 115 which is slow to release. 7^E opens circuit 11 so that M de-energizes. All the relays of the impulse responder are again at normal.

The second digit 1 is now sent by the caller and relay 1^E is first de-energized as before and 2^E remains energized. 3^E is also energized as circuit 3 is completed over H . Circuit 4 is therefore completed and L is energized. 7^E is not energized as the circuit is now open at 12^E . H is energized over 125 8 and M is energized over 11 to earth at 3^E . When 1^E is again energized H is retained over 4. H has opened circuit 3 so that 3^E de-energizes. Circuit 14 at relay 3^E must be made before 4 and 11 are broken, so that the 130

earth cut off may be replaced by earth over 21 without break. If necessary another slow release relay controlled by 3^E may be introduced which will keep earth on 4 and 11 after 3^E has joined up circuit 14. 14^E energizes in series with cut off relay C O R if the line called is idle. H and M are kept energized over circuit 21. 14^E is retained energized over 15 and C O R is retained energized over 21 and 14^E. The calling line is now extended to the called line by loop 16 and 17. Circuit 14 being the third conductor retaining circuit. Circuit 18 causes 18^E to energize to connect the calling line to the ringing generator with relay 19^E in series. 19^E does not respond with the called station condenser in series with the bell, but when the receiver is lifted to answer it energizes to complete circuit for 20^E which opens circuit 18 to join the lines through for talking. Relay 16^E is then energized.

The combination described places the power of release or disconnection in the hands of the calling party by replacing the receiver and opening the circuit of 1^E when all apparatus is restored to normal. Should he fail to release the connection the called party can deenergize 16^E when circuit 22 will be completed to glow lamp 22^L and/or give an audible signal.

Should the called party be engaged relay 14^E will not energize as the cut-off relay will

be earth connected and insufficient current will be obtainable. Circuit 21 will not be completed at 14^E and 3^E will deenergize and release H so that circuit 6 will be completed to energize 6^E, and local retaining circuit 6 made, and circuit 24 will be completed to connect the busy tone to the loop circuit.

Under certain conditions, particularly for small installations, the tens and units relays may be energized in reversed order, for example, what have been called the "tens" relays may become the "units" and the responder be afterward tied up to the units.

What I claim is:—

1. In a telephone system, the combination with a plurality of lines of a plurality of wires, a plurality of relays each adapted to connect a number of said lines to a corresponding number of said wires, each to each, and a plurality of combining relays less in number than said wires and adapted to complete a connection through any one of said wires.

2. In a telephone system, the combination with a plurality of lines of a plurality of wires, a group of relays each of which is adapted to connect each of the wires to a line, a junction and a second group of relays capable of being actuated alone or in combination and adapted to connect any one of the wires to the junction.

LEONARD CHARLES BYGRAVE.
